UNITED STATES PATENT OFFICE.

WILLIAM CARROLL, OF COLUMBUS, OHIO.

CLAMP.

SPECIFICATION forming part of Letters Patent No. 427,300, dated May 6, 1890.

Application filed May 10, 1889. Serial No. 310,279. (No model.)

To all whom it may concern:

Be it known that I, WILLIAM CARROLL, of Columbus, in the county of Franklin and State of Ohio, have invented a new and Improved Clamp, of which the following is a full, clear, and exact description.

The invention relates to stove-blocks and stove-clamps, such as shown and described in the United States Letters Patent Nos. 378,572 and 390,751, granted to me and C. A. Hill February 28, 1888, and October 9, 1888, respectively.

The object of the invention is to provide a new and improved clamp designed as a bench-clamp for pattern, cabinet, and box makers, and also for the use of stove-makers, serving to conveniently hold the doors of the stoves and other parts in place on the stove-casing while fitting on the pintles, hinges, &c.

The invention consists of a spring-pressed rod held to slide in a casing, a head held on the said rod, and a table held on the said casing.

The invention also consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a sectional side elevation of the improvement. Fig. 2 is a plan view of the table-bracket. Fig. 3 is a plan view of the hand-wheel, and Fig. 4 is a sectional plan view of the head on the line $\alpha\alpha$ of Fig. 1.

The improved clamp is provided with a cylindrical casing A, having at its bottom a base B, adapted to be secured to a table or bench, if used as a carpenter's clamp. In the cylindrical casing A is held a rod C, having its bearing in a head A', formed in the casing A. On the lower end of the rod C is held a collar D, fitting into the cylindrical casing A and supporting one end of the spring E, formed on the said rod C, and pressing at its other end against the head A', as is plainly shown in Fig. 1. On the outer end of the rod C is secured a handle F, which serves to raise or lower the rod C in the casing A. A set-

screw G screws in the head A' against the rod C, to lock the latter in place when raised or lowered to any desired position.

The outer end C' of the rod C is curved downward and is provided with a screw-thread C², on which screws a nut H, made in the form of a hand-wheel, as is plainly shown in Figs. 1 and 3. From the screw-threaded part C² of the rod C extends an offset C³, on which is held to slide the shank I' of a head I, preferably made in disk form. On the lower end of the said offset C³ is secured a collar J, fitting into the shank I' and supporting one end of the spring K, coiled around the said offset C³ and pressing against the upper end of the shank I', as is plainly shown in Fig. 1. In order to prevent the head I from turning on the offset C³, I provide the shank I' with grooves I², into which fit lugs J', projecting from the collar J. (See Fig. 4.)

On the casing A is held to slide vertically a bracket L, adapted to be secured in place on the said casing by a set-screw N, screwing in the bracket against the said casing. On the outer end of the bracket L and on top of the same is formed an aperture L', into which fits the lower half of a ball O, forming a shank for a table P, located directly beneath the head I. Around the aperture in the bracket L are formed a number of lugs L², which are bent over the upper part of the ball O when the latter is in place in the aperture L'. When the lugs L² are thus bent over, the ball O is prevented from passing out of the aperture L', while at the same time the lugs permit the turning of the ball and its table so that the latter can assume any desired inclination.

The operation is as follows: When the bracket L is secured on the casing A and the operator desires to clamp an article, he moves the handle F upward, so as to compress the spring E, and then places the article on the table P, after which the operator releases the pressure on the handle F. The rod C now moves downward by the action of the compressed spring E, so that the head I is pressed in contact with the top of the article resting on the table P. The rod C is then locked in place on the casing by the set-screw G. The article is thus clamped between the table P

- and the head I. When more pressure is desired, the operator turns the hand-wheel nut H so that the latter moves downward against the shank I' of the head I, whereby the latter 5 moves downward and into firm contact with the article to be clamped. As the table P is mounted to turn and to swing in the bracket L, it will adjust itself to any uneven surface of the article to be clamped. When the operator 10 desires to release the article clamped between the table P and the head I, he turns the hand-wheel nut H upward, whereby the spring K forces the head I upward out of contact with the article clamped. Thus it will be seen that a very simple and convenient device is provided for clamping any desired articles and releasing the same after the work has been accomplished.
- Having thus described my invention, what I claim as new, and desire to secure by Letters Patent, is—
1. In a clamp, the combination, with a casing, of a spring-pressed rod held to slide in the said casing, a head held adjustably on the outer downward-bent end of the said rod, and a table held adjustably on the said casing, substantially as shown and described.
  2. In a clamp, the combination, with a casing, of a spring-pressed rod held to slide in the said casing, a head held adjustably on the outer downward-bent end of the said rod, a table held adjustably on the said casing, and means, substantially as described, for adjusting the said head on the said rod, substantially as specified.
  3. In a clamp, the combination, with a casing, of a spring-pressed rod held to slide in the said casing, a head held adjustably on the outer downward-bent end of the said rod, a table held adjustably on the said casing, and a set-screw for locking the said rod in place on the said casing, substantially as shown and described.
  4. In a clamp, the combination, with a casing, of a spring-pressed rod held to slide in the said casing, a head held adjustably on the outer downward-bent end of the said rod, a table held adjustably on the said casing, a set-screw for locking the said rod in place on the said casing, and a handle for raising or

lowering the said rod, substantially as shown and described.

5. In a clamp, the combination, with a casing, of a spring-pressed rod held to slide in the said casing, a spring-pressed head held to slide on the bent end of the said rod, and means, substantially as described, for adjusting the said spring-pressed head on the said rod, as set forth. 55

6. In a clamp, the combination, with a casing, of a spring-pressed rod held to slide in the said casing, a spring-pressed head held to slide on the bent end of the said rod, means, substantially as described, for adjusting the said spring-pressed head on the said rod, and a table held adjustably on the said casing, substantially as shown and described. 60

7. In a clamp, the combination, with a casing, of a spring-pressed rod held to slide in the said casing, a spring-pressed head held to slide on the bent end of the said rod, means, substantially as described, for adjusting the said spring-pressed head on the said rod, a bracket held adjustably on the said casing, and a table mounted to turn on the said bracket and located beneath the said head, substantially as shown and described. 70

8. In a clamp, the combination, with a rod, of a spring-pressed head held to slide on the said rod, and a nut screwing on the said rod 80 against the said head, substantially as shown and described.

9. In a clamp, the combination, with a rod, of a head having a cylindrical shank held to slide on the said rod, a spring held in the said shank, and a nut screwing on the said rod against the said shank, substantially as shown and described. 85

10. In a clamp, the combination, with a rod, of a head having a cylindrical shank held to slide on the said rod, a spring held in the said shank, a nut screwing on the said rod against the said shank, and a collar secured on the end of the rod and supporting one end of the said spring, substantially as shown and described. 90

WILLIAM CARROLL.
